CIRCULAR KNITTING MACHINE

Frederick Edward Deans, Charles Frederick Manager, and George Alfred Buswell, Leicester, England, assignors to The Bentley Engineering Company Limited, Leicester, England, a British company

Application March 4, 1936, Serial No. 67,162
In Great Britain March 14, 1935

3 Claims. (Cl. 66—14)

This invention is concerned with improvements in or relating to circular knitting machines.

In application No. 667,444 filed April 22nd, 1933 there is disclosed a knitting machine which is arranged to knit a draw thread into the fabric, between adjacent articles of a string of articles knitted by the machine, to facilitate the subsequent separation of the articles from one another by withdrawal of the draw thread from the fabric. In said machine the draw thread is knitted at a feed point which is additional to the main feed point of the machine.

In British Patent No. 400,623, there is disclosed (see Figures 7 and 8 of the drawings of said patent) an arrangement whereby at the said additional feed point, there is provision for the knitting of a draw thread as above mentioned and also for the knitting of one layer of a French welt, the yarn for the French welt being supplied from a second yarn-feeder provided for that purpose.

In a machine embodying features of the present invention, the second yarn-feeder above referred to is utilized to feed yarn to one or both sets of the needles at the additional feed point simultaneously with the feeding of yarn to the same set or sets of needles at the main feed point, with the result that the knitted fabric (plain or ribbed as the case may be) is composed of two helices of yarn, which yarns may be of a contrasting nature, say differing in colour.

In the knitting of a hose or half-hose by a machine according to said British Patent No. 400,623, a series of operations involving the introduction and withdrawal of the stitch cam of the additional feed point into and from its working position—each of which events occurs in two separate stages—and the movements of the two yarn-feeders of that feed point into and out of feeding position, has to occur in a definite order and in a definite timing in relation to the rotation of the needle cylinders and to other operations performed by the machine. This series of operations is effected by an operating mechanism which starting from an initial position operates said stitch cam, yarn feeders and thread trapper and cutter devices associated with the yarn feeders, in a series of steps. At the completion of said series of steps, the operating mechanism automatically ceases to operate. The series of operations above referred to occurs during the knitting of a relatively small portion of the hose or the like i. e. that portion of the hose in the general neighbourhood of the welt. In a machine of the present invention however the sec-

ond yarn feeder has movements into and out of feeding position at relatively widely separated portions of the hose. For instance, the second yarn feeder moves into feeding position for the knitting of the leg portion of the hose from yarn fed from both feed points, moves out of feeding position for the knitting of the heel pouch from yarn fed only at the main feed point, moves again into feeding position for the knitting of the foot portion from the said two yarns, and finally moves out of feeding position for the knitting of the toe pouch from yarn fed only from the main feed point. The series of steps in which the devices at the additional feed point are operated is thus formed into a plurality of sections brought about by pauses in the operative movements of said operating mechanism. These pauses are effected automatically, the operating mechanism starting and stopping its operative movements at the beginning and end, respectively, of each of the sections. Now, if the operator found it necessary, say by reason of breakage of yarn, to start the knitting of a fresh article before the knitting of the preceding article in the string was finished, the operating mechanism for the devices at the additional feed point, in such circumstances, would in all probability not be in its initial starting position, and consequently would be out of step with the rest of the machine when the machine was started for the knitting of the new article. With a view to preventing such a situation arising, the present invention provides a correcting mechanism which returns the operating mechanism to its initial position if it has accidentally been displaced therefrom and therefore not in step with the rest of the machine.

In application No. 713,732 filed March 2nd, 1934 there is described a method of anchoring the ends of an additional helix of yarn which is knitted into the fabric at a portion thereof, from yarn supplied at an additional feed point, the ends of the additional helix being knitted into the fabric at the main feed point. In knitting machines as usually constructed and in cases in which the knitting of an additional helix is to stop just prior to the knitting of a heel or toe pouch, it is not possible to anchor the finishing end of the additional helix by the method above referred to for the reason which will now appear. Immediately preceding the knitting of a pouch, the needles of about one half the needle circle are rendered inoperative, the sliders for these needles having for this purpose long butts which can engage a cam brought into action at that time which moves the needles to non-knitting

position. The sliders for the rest of the needles, i. e. those which are concerned in the knitting of the pouch, have short butts which are not long enough to engage the cam just referred to and consequently are not affected by it. In the machine described in said British Patent No. 400,623, the stopping of the knitting at the additional feed point is done in two stages. In the first stage, the stitch cam (or a bolt cam associated with the stitch cam) at that feed point, while the long butts are being acted upon by it, is moved outwardly from the needle cylinder a distance sufficient to permit the short butts later on to pass it unaffected but not sufficient for it to lose control of the long butts. At the second stage, the stitch cam is moved fully outward, out of range of the long butts, while the short butts are passing it. From the foregoing it will be apparent that the last needle to engage the stitch cam and therefore to knit at the additional feed point, is a needle associated with a long-butt slider, which needle is then moved to non-knitting position by the cam aforesaid acting upon the long butt of its slider. Hence this needle and the long-butt-slider needles adjacent to it no longer knit and the loose end of the yarn fed from and severed at the additional feed point cannot therefore be knitted into the fabric at the main feed point as required by the said method.

To obviate the above difficulty, the present invention provides an arrangement in which between the long-butt sliders and the short-butt sliders there are situated a few (say six or eight) sliders having butts of medium length and the cam which engages the long-butt sliders to move their needles to non-knitting position for the operation of pouch formation, is adapted (for instance by being made narrower than usual) to permit the medium-butt sliders to pass it without being engaged by it. The medium butts, however, are long enough to engage the stitch cam at the additional feed point when the stitch cam is in the first of its two stages of withdrawal from operative position. Hence, at this time, the needles associated with the medium-butt sliders will knit at the additional feed point, and as they will not be moved to non-knitting position by the cam aforesaid, the loose yarn end held by them will be knitted into the fabric at the main feed point.

A construction of mechanism, illustrative of the present invention, will now be described with the aid of the accompanying drawings, and by way of example will be considered as applied to a machine of the kind described in said British Patent No. 400,623.

In the drawings:—

Figure 1 is an elevation of part of the machine showing the lower or plain needle cylinder and devices associated with an additional feed point including a stitch cam for that needle cylinder;

Figure 2 is a plan of parts seen in Figure 1;

Figure 3 is an elevation of mechanism concerned in the operation of the devices at the additional feed point;

Figure 4 shows in plan and partly in section, parts seen in Figure 3; and

Figure 5 is a diagram hereinafter referred to.

The machine described herein will be considered as arranged to knit ribbed hose or half-hose in the usual string formation, with a draw thread included between adjacent articles, each article having the usual type of welt, and with its sole portion and heel and toe pouches knitted in plain fabric as is customary. The major portion of the

hose including the sole, but not of course the pouches, will be knitted in two helices of yarn supplied from both feed points.

The machine to which the present correcting mechanism is applied, is provided with the customary control drum by rotation of which various changes in the knitting operation are brought about, the rotation of the control drum being controlled, as usual, by the main pattern chain (not shown) of the machine, which chain travels in timed relation with the rotation of the needle cylinders.

The operating mechanism of the present machine for the devices of the additional feed point, in general, is similar to the corresponding mechanism described in said British Patent No. 400,623 in connection with Figures 7 and 8 of the drawings thereof, and the driving and timing devices for that mechanism are, in the main, alike in the two machines.

The additional feed point comprises a stitch cam 14 located in the cam box for the lower or plain needle cylinder 12, a feeder 220 for the draw thread, a feeder 268 for the yarn of the helix that is knitted at this feed point, a trapper 23 and cutter device 238 associated with the feeder 220, and a similar device 284 associated with the feeder 268.

These devices are operated by a set of cams mounted upon and rotatable with a shaft 94. The cam 294 operates the stitch cam 14, the cams 234 and 280, respectively, operate the feeders 220 and 268, and the cams 256 and 292, respectively, operate the trapper and cutter devices 238 and 284. In the drawings these cams are shown diagrammatically as plain circular discs, i. e. no attempt has been made to indicate the peripheral configuration which in practice the cams possess. In the present machine the feeder 268 is mounted upon its supporting spindle 270 so as to be able to swing in a vertical plane about a pivot 500, a spring 502 serving to press the tail end of the feeder against a cam plate 504 which guides the feeding end of the feeder 268 over its companion feeder 220, as the feeder 268 moves between feeding and idle positions.

The driving mechanism for the cam-carrying shaft 94 is shown in Figures 3 and 4. This mechanism comprises a ratchet wheel 100 which is operated by a pawl 102, pivoted at 104 on a lever 106, a spring 108 (Figure 3) tending to maintain the pawl 102 in engagement with the ratchet wheel. The lever 106 is pivoted at 109 on a bracket 110 secured to a fixed part 52. The lever 106 is actuated by a cam 112 through the agency of a push rod 114 which, as presently will be explained, is moved laterally into and out of the path of the cam 112, so as to start and stop, respectively, the driving action of the cam 112 upon the pawl and ratchet device 100, 102. The cam 112 has two rises and falls and is attached to a part of the machine (a bevel gear wheel 116) which revolves at the same speed as the needle cylinder and so gives two movements to the vertical shaft 94 for each revolution of the needle cylinder when the push rod 114 is in the path of the cam 112. The push rod 114 is mounted to slide in a guideway formed in a lever 118 which is fixed on a shaft 120, journalled in bearings 122 on a fixed part of the machine frame. The lever 118 is moved by connections between it and cams on the control drum 126 of the machine one of which cams is shown at 124, so that at predetermined times it moves the push rod 114 into and out of the path of the cam 112. The

idle track for the push rod 114 is round the outside of the cam 112. The connections between the control drum 126 and the lever 118 comprise a lever 128 fixed to the shaft 120, and a 5 push rod 130, which passes through an eye in the end of the lever 128 and is operated by the cams 124 on the control drum 126. The push rod 130 operates the lever 128 through a spring 132, so that, should the cam 124 come into operation (either when the control drum 126 is 10 being turned by hand, or otherwise) at a time when the push rod 114 is in its idle track i. e. on the outer side of the cam 112, the push rod 114 will be pressed against the side of the cam 112 15 and the spring 132 will be compressed until the end of the cam 112 has passed the push rod 114 when the latter will spring into the track of the cam 112. A spring 134 serves to return the push rod 114 to its idle track after the required number 20 of turning movements has been given to the vertical shaft 94 by the mechanism just described.

In the present machine, the cam-carrying shaft 94 makes one complete revolution during the knitting of each article, and the ratchet wheel 25 100 which is driven by the pawl 102, has eighteen teeth (pins). The cams on the shaft 94 which operate the two feeders 220, 268, the two trapper and cutter devices 238, 284, and the stitch cam 14 are of single formation, i. e. they are so 30 formed as to impart but one complete operation or series of operations appropriate to a single article upon the devices they actuate, during each revolution of the shaft 94.

During the knitting of an article the operating 35 mechanism for the devices at the additional feed point acts as follows: The first movement of the shaft 94 is idle, that is to say, the shape and disposition of the cams upon it are such that no movement is given by the cams to the devices which they operate. At this time the long butt needle-sliders are passing the position of the stitch cam 14 which accordingly must not be moved inwardly otherwise these butts would be damaged. The second movement of the shaft 40 45 94 causes the stitch cam 14 to be given its first stage of inward movement which occurs during passage of the short butt needle-sliders past the stitch cam position, thus bringing the stitch cam 14 into the path of movement of the long butts but permitting the short butts to pass it unaffected. At this time the draw thread feeder 220 50 is moved into feeding position in readiness for the draw thread to be taken by the needles of the long butt sliders when these are acted upon by the stitch cam 14. At the third movement of the shaft 94, the stitch cam 14 is given the second stage of its inward movement while the long butts are being acted upon by it, so that the stitch cam 14 can act also upon the short butts when 55 60 65 these reach this stitch cam. And the trapper 238 is opened to release the end of the draw thread which is now being knitted into the fabric at the additional feed point by needles of the bottom cylinder while rib-knitting is being effected at the main feed point. The fourth movement of the shaft 94 is an idle one. On the fifth movement of shaft 94 the stitch cam 14 is given the first stage of its outward movement while the long butts are being acted upon by it. On the 70 75 sixth movement of shaft 94, the stitch cam 14, while the short butts are passing its position, is given the second stage of its outward movement, and at the same time the draw thread feeder 220 moves into inoperative position and the draw thread is trapped and cut by the trapper and

cutter device 238. This completes the operation of the knitting of the draw thread into the fabric.

The machine next forms the welt in the usual manner at the main feed point.

After the welt is knitted, the shaft 94 is given 5 its seventh movement which, however, is an idle one. The eighth movement of the shaft 94 gives to the stitch cam 14 its first stage of inward movement, while the short butts are passing its position, and also brings the second yarn-feeder 10 15 268 into position to feed yarn to the needles of the long butt sliders when these butts in their turn reach and are acted upon by the stitch cam 14. The ninth movement of the shaft 94 gives to the stitch cam 14 the second stage of its inward movement in readiness to engage the short butts when these arrive at that cam, and the trapper 284 is opened to release the end of the 20 25 30 yarn fed from the second yarn-feeder 268. The tenth movement of shaft 94 is idle. The fabric is now being knitted in two helices, one derived from yarn supplied at the main feed point and the other from yarn supplied at the additional feed point, and the otherwise loose end of the latter yarn will have been knitted into the fabric 35 at the main feed point in accordance with the method hereinbefore referred to. The appropriate cams of the machine will also have been automatically so adjusted that rib-knitting is effected at both feed points, the machine being 40 provided, of course, at the additional feed point with a rib-stitch cam in the upper needle cylinder which cam is automatically adjusted into operative position when rib-knitting at that feed point is to be performed.

Rib-knitting now continues at both feed points until the heel pouch is to be knitted. At about this time the shaft 94 is given its eleventh movement during which the stitch cam 14 is given the first stage of its outward movement as the 45 50 55 long butts are being acted upon by it. The twelfth movement of shaft 94 gives to the stitch cam 14 the second stage of its outward movement where it is out of range of all the butts and consequently knitting at the additional feed point ceases. During this movement of the shaft 94 the said second feeder 268 is moved into inoperative position and the yarn issuing from it is 60 65 70 75 80 85 90 95 100 trapped and cut by the trapper and cutter device 284.

As before explained, in order to anchor at the main feed point this end of the yarn supplied from the second feeder at the additional feed point a few needle sliders (as shown in the diagram, Figure 5, of the needle circle) having medium-length butts 506 are inserted between the long-butt sliders 508 and short-butt sliders 510, which medium-length butts 506 can engage the stitch cam 14 of the additional feed point when that cam is in the first stage of its outward movement, but are not long enough to engage the cam aforesaid which, at the appropriate time, is automatically adjusted into position to engage the long-butt sliders 508 and move their needles to non-knitting position.

After the knitting of the heel pouch by the usual reciprocatory movement of the machine, rotary knitting is resumed for the foot part of the article with yarn supplied from both feed points, the starting of knitting at the additional feed point being effected by movements thirteen to sixteen of the shaft 94, which movements correspond with the seventh, eighth, ninth and tenth movements of that shaft and accordingly need not be described.

When the toe pouch is to be knitted, the shaft 94 makes its seventeenth and eighteenth movements, which correspond with its eleventh and twelfth movements already described, to suspend 5 knitting at the additional feed point. The article is then completed by the knitting of the toe pouch in the usual manner. It will be understood that the ends of the yarn fed from the additional feed point during the knitting of the 10 foot part of the article are also anchored in the fabric by the method hereinbefore referred to.

From the foregoing it will be appreciated that the eighteen movements of the shaft 94 are broken up into sections by pauses in those movements. In order to ensure that the movements constituting each section shall be completed even though the control drum 126 is moved on so that the push rod 130 is free to fall off the end of the cam 124 which operated it, the following mechanism is provided:—The ratchet wheel 100 has formed in it, a series of notches 136 and a tooth 138 at one end of a bell-crank lever 140 is adapted to engage these notches. The other end 142 of said lever lies alongside (i. e. below as seen in Figure 4) a projection 144 on the lever 118 if the push rod 114 in that lever is in its idle track. The lever 140 is pivoted at 146 on the bracket 110 and the tooth 138, for the purpose of adjustment may, as shown, be formed on a block 148 adjustably secured to the lever end by a screw 150. In the position just described the vertical shaft 94 cannot be rotated as the projection 144 prevents the lever 140 from being turned in a direction which would remove the tooth 138 from the notch 136 35 with which it is engaged. When the lever 118 is moved in the operative position (as shown in Figures 3 and 4) by the action of a cam 124 on the control drum 126, the first movement of the ratchet wheel 100 places the end 142 of the lever 40 140 behind (i. e. as shown in Figure 4) the projection 144. The lever 118 is thereby held in its operative position, irrespective of the position of the control drum 126 until the tooth 138 on the lever 140 falls into a notch 136 by the action of a 45 spring 152. The push rod 114 is then sprung back to its idle track by the action of the spring 134. A spring 154 (Figure 4) connected to the lever 106 and to a fixed part 156 tends to keep the lever pressed against the push rod 114. 50 From the foregoing it will be appreciated that provided the shaft 94 is in its correct angular position in relation to its driving mechanism (which comprises the cam 112 and the pawl 102 operated by that cam) there is but little probability that the timing of the movements of the shaft 94 in relation to the timing of other associated devices of the machine, will be disturbed. The timing of the said driving mechanism in relation to the rotation of the needle cylinders, is 60 taken care of by the provision of a curved plate 113 (Figure 3) which is attached to the cam 112 and closes one of the gaps between the contiguous ends of the two portions of the cam 112.

In order to ensure that the shaft 94 is in its correct starting position before the knitting of an article by the machine is begun, the following correcting mechanism is provided which will automatically return the shaft to its starting position should it have been accidentally displaced 70 therefrom.

This correcting mechanism comprises a spring-controlled correcting rod 512 similar to the rod 130 and located below and somewhat to one side of the rod 130. One end of the correcting rod 75 512 is adjacent the control drum 126 and the

other end of this rod is connected by an adjustable vertically-disposed link 514 to one end of a lever 516 arranged to turn about a pivot pin 518 carried on the bracket 110. The other end of this lever is upturned to form a cam follower arranged in the path of a cam 520 on the underside of the ratchet wheel 100 on the shaft 94. Secured to the shaft 120 and arranged alongside the lever 128 is a depending arm 522, the lower end of which is just above a collar 524 10 on the correcting rod 512. This collar 524 is loose on the rod 512 but is backed up by a spring 526 that encircles the rod and bears against a collar 528 fast to the rod. The correcting rod 512 is moved endwise at times by a cam 530 on 15 the control drum 126.

If the shaft 94 is in its correct starting position, the correcting rod 512 will merely be moved endwise idly against the action of its spring 513 by the cam 530 on the control drum 126. But if 20 the shaft 94 is displaced from its starting position, the cam 520 on the ratchet wheel 100 will depress one end of the lever 516, thereby raising its other end and lifting the correcting rod 512 so as to bring the loose collar 524 thereon alongside the free end of the depending arm 522. When therefore the correcting rod 512 is moved endwise by the cam 530 on the control drum 126, the loose collar 524 on the rod will engage the depending arm 522 and, by way of force transmitted by the spring 526 on the rod, will turn the shaft 120 in a direction to bring the push rod 114 into the path of the cam 112 and thereby start the driving mechanism for the shaft 94 25 into action. The shaft 94 will thus be turned 30 until it arrives in its starting position wherein the cam 520 on the ratchet wheel 100 will have been removed from engagement with the follower of the lever 516, permitting the lever 516 to turn and thereby allow the correcting rod 512 to fall 35 into its lower and idle position.

Although in the foregoing description the controlling mechanism has been described as giving various movements to the stitch cam of the additional feed point, in practice it is preferred to 45 give such movements to a pilot cam which, when operative, deflects the slider-butts to the stitch cam proper. Further, this stitch cam itself is preferably made adjustable for stitch-length variation conveniently by means of operative connections between it and the mechanism for similarly adjusting the stitch cam of the main feed point.

We claim:

1. A knitting machine comprising a stitch cam 55 movable between a needle-actuating position and an idle position, a plurality of thread feeders each independently movable between a thread-feeding position and an idle position, thread trapper and cutter devices each associated, respectively, with one of said feeders to trap and cut and to release thread fed from said thread feeder, operating mechanism for operating said stitch cam, thread feeders, and trapper and cutter devices, which operating mechanism during 60 the knitting of an article by the machine is moved from an initial position in a series of steps formed into sections by pauses in the movement of said mechanism at predetermined points in the operation of the machine, driving means for driving 65 said mechanism, stopping means for automatically stopping the driving action of said driving means at the end of each of said sections, starting means for starting said driving action at the beginning of each of said sections, pattern 70 75 80 85 90 95 100

control means, devices on said pattern control means for actuating said starting means, and a correcting mechanism comprising an adjustable element, operative connections between said element and said operating mechanism arranged to maintain said element normally in operative relation with said starting means but to move said element out of such relation when the said operating mechanism is in its initial position, and a device on the pattern control means for operating said element at a time in the operation of the machine at which the operating mechanism should be in its initial position, whereby if the relation between the pattern control means and the operating mechanism has been disturbed, the starting means will be actuated by said element and will cause the driving means to drive the operating mechanism into its initial position.

2. A knitting machine comprising a stitch cam movable between a needle-actuating position and an idle position, a plurality of thread feeders each independently movable between a thread-feeding position and an idle position, thread trapper and cutter devices each associated, respectively, with one of said feeders to trap and cut and to release thread fed from said thread feeder, operating mechanism movable from an initial position in a series of steps for operating said stitch cam, thread feeders, and trapper and cutter devices, pattern control means for starting said operating mechanism into operation from said initial position and for thereafter stopping and restarting said mechanism thereby forming said series of steps into sections, driving means for said operating mechanism comprising a continuously moving cam, a pawl and ratchet device, and operative connections between said cam and device whereby said device is adapted to be driven by said cam, a disconnectable element in said operative connections under control of the said devices on the control drum, a locking device operated by the pawl and ratchet device for maintaining said element in connecting position until each section of said series of steps is completed, a cam driven by said pawl and ratchet device, a member adjustable into and out of operative connection with said disconnectable element, operative connections between said last-named cam and said member for effecting such adjustment of said member, and a device on the control drum for actuating said member.

pleted, and means operatively connected with the pawl and ratchet device and also under control of said pattern control means for moving said disconnectable element into connecting position if the correct positional relationship of the pawl and ratchet device with the pattern control means is disturbed.

3. A knitting machine comprising a stitch cam movable between a needle-actuating position and an idle position, a plurality of thread feeders each independently movable between a thread-feeding position and an idle position, thread trapper and cutter devices each associated, respectively, with one of said feeders to trap and cut and to release thread fed from said thread feeder, operating mechanism movable from an initial position in a series of steps for operating said stitch cam, thread feeders, and trappers and cutter devices, a control drum, devices carried thereby for starting said operating mechanism into operation from said initial position and for thereafter stopping and restarting said mechanism thereby forming said series of steps into sections, driving means for said operating mechanism comprising a continuously moving cam, a pawl and ratchet device and operative connections between said cam and device whereby said device is adapted to be driven by said cam, a disconnectable element in said operative connections under control of the said devices on the control drum, a locking device operated by the pawl and ratchet device for maintaining said element in connecting position until each section of said series of steps is completed, a cam driven by said pawl and ratchet device, a member adjustable into and out of operative connection with said disconnectable element, operative connections between said last-named cam and said member for effecting such adjustment of said member, and a device on the control drum for actuating said member.

FREDERICK EDWARD DEANS.
